WARNING SIGNAL

Fred William Billig, Jackson, Mich., assignor to
 The Sparks-Witthington Company, Jackson,
 Mich., a corporation of Michigan

Application May 18, 1933, Serial No. 671,671

4 Claims. (Cl. 116—137)

This invention relates to improvements in warning signals and pertains more particularly to that class of signals used on power-driven vehicles such as automobiles, motorboats or the like.

The main object of this invention is the production of a warning signal having improved tone characteristics preferably resulting in a pleasing harmonious tone highly effective in attracting the attention of one to be warned.

A further and important object resides in the production of a comparatively simple construction consisting of few parts, but constituting a rigid assembly and which can be economically manufactured.

Another object of the invention is to produce a signal of the above-mentioned class, which may be readily altered so as to produce tones of higher or lower pitch so that the signals may be used in pairs, with the signals of each pair having tones of different pitch and which are in concord with each other.

Other objects and advantages pertaining to the details of the structure will appear from the following description, taken in connection with the accompanying drawing in which:

Figure 1 is a perspective view of a signal device embodying the various features of this invention.

Figure 2 is an enlarged longitudinal sectional view taken substantially in the plane of the line 2—2, Figure 1.

The warning signal, as illustrated in the drawing, is of the magnetically operated vibrating diaphragm type and comprises a circular diaphragm 1 secured at its edge between a case 2 and the front covering or housing 3 by bolts or screws 4. The case 2 has its central portion dished and of substantially cylindrical cup-shape, with the center of said cup-shaped portion provided with an opening for the reception of a magnet or magnetic field 5. The magnet 5 may be secured to the case 2 in any suitable manner not herein necessary to illustrate or describe.

The magnet 5 is provided with a central passage 6 therethrough and a pair of transversely disposed slots or grooves 7 formed in the rear face thereof. These slots 7 are arranged one at either side of the passage 6 and supportably receive therein a field coil 8. This field coil lies wholly forward of the rear surface of the magnet 5.

The diaphragm 1 is provided with a central opening in alignment with the opening 6 in the magnet 5. An internally threaded reinforcing collar or ring 10 is positioned in the opening in

the diaphragm 1 and rigidly secured in any suitable manner to that portion of the diaphragm adjacent said opening.

A sleeve 11 provided with an externally threaded portion is screw-threaded in the collar 10 so as to constitute a rigid portion of the diaphragm. One end of the sleeve 11 projects forwardly from the diaphragm and is flattened upon diametrically opposite sides for the reception of a disk or plate 12 which has a non-circular opening adapted to fit over the end of the sleeve 11, said disk being of sufficient diameter to extend across the adjacent face of the collar 10, and is adapted to be used to rotate the sleeve 11. The other end of the sleeve 11 extends inwardly some distance from the diaphragm through the central opening in the magnet 5 into engagement with the armature 9.

The inner end of the sleeve 11 is spherically shaped so as to seat tightly in a substantially similarly spherically shaped recess in the adjacent side of the armature 9. The armature 9 has a central hole 13 extending therethrough in alignment with the interior of the sleeve 11 and is provided on the inner face thereof with a recess in alignment with the hole 13 and which receives a spacing collar 14 which has the inner face thereof in engagement with a washer 15 interposed between the spacing collar 14 and a leaf spring 16 which is supported at one end by a pedestal 17 secured to or made integral with the inner face of the case 2 at one side of the magnet opening.

In order that the spacing collar 14 and the washer 15 may have an adjustable firm contact with each other, the inner end of the collar 14 is preferably of convex form, while the adjacent face of the washer 15 is concaved to conform to the curvature of the collar 14.

The spring 16, washer 15, spacing collar 14, armature 9 and sleeve 11 are rigidly secured together in fixed relation with each other and with the diaphragm 1 by means of a headed bolt 19 and a nut 20, said bolt being extended upwardly through the sleeve 11, armature 9, collar 14, washer 15 and spring 16, while the nut 20 is screw-threaded on the inner end portion of the bolt 19 in contact with the spring 16. I preferably provide a washer as 21 upon the bolt 19 between the head of the bolt and the disk 12 for engaging said disk as the disk is clamped between the head of the bolt and the outer end of the collar 10 so that when the sleeve 11 and the associated parts are secured together by the bolt 19 and nut 20, said disk 12 and the sleeve 11 will be locked in

the adjusted position and thereby maintain the armature 9 and the diaphragm 1 in fixed predetermined spaced relation for maintaining the armature 9 in slightly spaced relation with the 5 inner face of the magnet 5, as illustrated in Figure 2, when the diaphragm 1 is in the normal at-rest position.

There is also provided a make and break mechanism for the circuit of the field coil 8 and which 10 consists of a pair of electrodes or contact members 23 and 24. One of the electrodes as 23 consists of a screw adjustably mounted in one end of a yoke 25 which has the other end secured to the pedestal 17 in insulated spaced relation there- 15 to, while the other electrode is a stud secured to the free end portion of a flat spring member 26 which is secured to the pedestal 17 in insulated spaced relation to the pedestal and also to the yoke 25.

20 The spring member or contact arm 26 extends inwardly from the contact member 24 to within a short distance of the upper end of the screw 19 in the path of movement of a nut or actuating member 27 which is screw-threaded on the upper end of the screw 19 and is locked to the screw in predetermined relation with the inner end of the member 26 by means of a lock nut 28 so that when the armature 9 is drawn towards the magnet 5, the electrodes 23 and 24 will be separated. 25 The upper face of the contact arm 26 is preferably provided with an insulating material for maintaining the screw 19 and contact member 24 in insulated spaced relation during the engagement of the actuating member 27 with the contact arm 26.

30 A cover 29 is also provided for enclosing the magnet 5, the case 2 and the parts associated therewith, said cover being secured in position by means of a U-shaped bracket 30 which extends diametrically across the case 2, with the ends 35 thereof secured to said case by the bolts 4 or other suitable means and a screw 31 which secures the cover 29 to the bracket 30.

The cover 29 may be provided with a suitable 40 aperture as 29' through which electrical conductors not shown may pass to the interior of the case and be secured to suitable terminals, one of which is illustrated at 60, Figure 2, secured to the case 2.

45 A fixed condenser 34 is secured to one side of the magnet 5 by a spring clip 35, said condenser being electrically connected with the coil 8 and contacts 24 and 25 in any well-known manner not herein necessary to further illustrate or de- 50 scribe.

55 It will now be observed that the mechanism thus far described constitutes a conventionally constructed motor of the magnetic type adapted to produce vibratory movement of the diaphragm 1 when electric energy of proper potential is supplied to the coil 8.

The main features of this invention reside in the form and construction of the front covering or housing 3 and an air conduit as 37 associated 60 with the housing. It will be observed by referring to Figure 2 that the central portion of the diaphragm 1 is of serpentine formation in cross-section and that the inner face of the housing 3 is also formed serpentine in cross-section to con- 65 form to the contour of the adjacent portion of the diaphragm 1.

70 The outer edge of the diaphragm 1 is prefer- ably spaced from the housing 3 by a ring or washer 38 so as to provide an air chamber 39 between 75 the housing 3 and the diaphragm 1. The central

portion of the diaphragm, in this instance, is spaced a greater distance from the adjacent portion of the housing 3 than the outer edge thereof so as to permit the free vibratory movement of the diaphragm as the armature 9 moves to and from the inner face of the magnet 5.

5 The housing 3 is also provided with a centrally located hollow boss 40 which is adapted to receive the outer end of the screw 19 and collar 10 there- 10 in. The boss 40 is internally threaded for receiv- ing one end of an externally threaded bracket 41 which may be secured to the housing 3 by a lock nut 42. The bracket 41 is provided with an air passage 43 which extends from the inner 15 end of the bracket outwardly and terminates at the side of the bracket intermediate the ends thereof.

A tube 44 having the ends thereof return bent to form an air column coil, is removably secured at one end to the bracket 41 by a nut 45 in communication with the air passage 43, while the other end of the tube 44 is removably secured by a nut 46 to the outer end of the bracket 41 in communication with a transversely disposed pas- 20 sage 47 provided in the outer end of the bracket. 25

I also provide a projector tube 49 which consists of a conical body portion 50 which has the smaller end thereof secured to the outer end of the bracket 41 in communication with the pas- 30 sage 47 and a bell portion 51 which may be se- cured to the other or larger end of the tube 50 in any suitable manner as by forming a bead 52 on the outer end of the portion 50 and an annular groove 53 in the bell portion 50 adapted to receive the bead 52 therein.

I also provide the projector 49 with a baffle screen 54 which consists of wire mesh concavo-convex in cross-section, with the edge thereof re- 35 movably mounted in an annular recess formed at the interior of the body portion 50 adjacent the bead 52.

40 It will now be observed that inasmuch as the loudness or intensity of sound is proportionate to the force of the shock which the air receives, the density of the medium through which the air waves pass and the obstruction in the path of said air waves and that as pitch is coordinate with force, timbre and duration, the tone of the signaling device may be readily changed by alter- 45

ing the thickness of the diaphragm 1, the air gap between the armature 9 and magnet 5 and the length of the air column tube 44. In other words, by constructing the instrument as illus- 50 trated in the drawing, a low pitch tone is ob- tained, and when a high pitch tone is desired, it is only necessary to substitute for the diaphragm shown, one of a different thickness, to alter the air gap between the armature 9 and the magnet 5 by manipulating the sleeve 11 relative to the diaphragm 1 and collar 10 and by providing an air column tube 44 of less length than the one 55 illustrated in the drawing, and although I have shown and particularly described the preferred embodiment of my invention, I do not wish to be limited to the exact construction shown, as various changes both in the form and relation of the parts thereof, may readily be made without departing from the spirit of this invention, as set forth in the appended claims.

60 I claim:

65 1. In a warning signal, a case, a diaphragm, a housing means securing the diaphragm and hous- ing to the case to form an air chamber adjacent one side of the diaphragm, a motor mounted on the case and operatively associated with the di- 70

- aphragm for producing a vibratory movement of said diaphragm, and an air conduit for amplifying the sound waves produced by the diaphragm comprising a bracket secured to the housing and 5 having an air passage therein in communication with the chamber, a projector tube secured to the bracket and an air column tube removably secured to the bracket with one end in communication with the interior of the projector tube 10 and the other end in communication with the passage in the bracket.
2. In a warning signal, a diaphragm, a housing secured at one side of the diaphragm to form an air chamber therebetween, said housing being 15 provided with a central opening leading outwardly from the air chamber, a bracket adjustably secured to the housing at said opening, said bracket being provided with an air passage therein leading from the end of the bracket in communication 20 with said opening to the exterior of the bracket at one side thereof and a transversely disposed air passage spaced from the first-mentioned air passage, an air column tube secured to the bracket with each end thereof in communication with a 25 respective air passage, a projector tube secured at one end to the bracket with the interior thereof in communication with said transversely disposed air passage, and means for providing a vibratory movement of said diaphragm.
- 30 3. A warning signal comprising in combination, a diaphragm, a housing secured at one side of the diaphragm to form an air chamber therebetween, said housing being provided with an opening leading outwardly from the air chamber, a bracket secured to the housing at said opening, said bracket being provided with an air passage therein in communication with said opening, and a second air passage spaced from the first mentioned air passage, an air column tube secured to the bracket and operatively connecting said 10 passages with each other, a projector tube secured at one end to the bracket with the interior thereof in communication with said second mentioned air passage and means for producing a vibratory movement of said diaphragm.
2. In a warning signal comprising in combination a diaphragm, a housing secured at one side of the diaphragm to form an air chamber therebetween, said housing being provided with an air passage leading outwardly from the air chamber and a second air passage spaced from the first mentioned air passage, an air column tube secured to the housing and operatively connecting said air passages with each other, a projector tube secured at one end to the housing means with the interior thereof in communication with said second mentioned air passage, and means for producing a vibratory movement of said diaphragm.
3. A warning signal comprising in combination, a diaphragm, a housing secured at one side of the diaphragm to form an air chamber therebetween, said housing being provided with an opening leading outwardly from the air chamber, a bracket secured to the housing at said opening, said bracket being provided with an air passage therein in communication with said opening, and a second air passage spaced from the first mentioned air passage, an air column tube secured to the bracket and operatively connecting said 10 passages with each other, a projector tube secured at one end to the bracket with the interior thereof in communication with said second mentioned air passage and means for producing a vibratory movement of said diaphragm.

FRED WILLIAM BILLIG. 30
